TIME-ADVANCED ACTUATING DEVICE FOR
WEAVING LOOM STOP-MOTIONSJaime Picanol, Zandberg, Zillebeke-lez-Ypres,
Belgium

Application September 27, 1951, Serial No. 248,614

5 Claims. (Cl. 139—345)

1

The invention relates to weaving looms with a fast-reed in which the stopping of the loom, when the shuttle does not arrive in the shuttlebox at the proper time, is effected by means of the buffers placed on both sides of the loom.

The aim of the invention is to reduce the shock produced by the stopping of the loom batten through the buffers. This result is, according to the invention, obtained by time advancing the actuation of the stop-motion device. In the conventional looms, the time elapsing between the moment when the noses of the stop rods abut the stops on the buffers and the moment of the release of the operating lever for the stop-motion or clutch mechanism of the driving motor, is such that the resulting shock is relatively great because the driving couple subsists until said clutch or stop-motion is actuated. Such shocks have, of course, an adverse effect on the loom.

According to the invention, the actuation of the stop-motion mechanism is time advanced or, comparatively to the conventional looms, anticipated in such a manner that the declutching of the motor is made independent of the moment of release of said operating lever, or, in other words, independent of the time elapsing between the contact of the stop-rod noses with the stops of the buffers, and the release of the operating lever of the stop-motion mechanism.

According to the invention, this time-advanced or anticipated actuation of the stop-motion mechanism is produced by the fact that the buffer or an element in contact with or mechanically linked to the buffer, actuates, right at the start of the backward movement of said buffer, a mechanism capable of operating the stop-motion device before the actual stopping of the loom.

The special mechanism interposed between the clutch and the buffer or any organ displaceable therewith is essentially variable and will be adapted, for instance, to the kind of clutch used.

As an example, and without any restrictive or limitative character, an embodiment of such a mechanism, capable to time-advance the declutching of the driving motor is described hereafter as applied to a clutch which is described more fully in my co-pending patent application of even date, Ser. No. 248,608. Reference is made to the accompanying drawings in which:

Figure 1 is a schematic side elevation of the device according to the invention;

Figure 2 is a plan view of the device according to the invention shown at rest;

Figure 3 is a view similar to Figure 2, the device being shown in a working position.

2

The loom must be stopped instantaneously whenever the shuttle does not reach the shuttlebox at the proper time. To achieve this result, the loom comprises a stop-rod 2 secured to the batten 1 and provided with noses 3, which are duly controlled by the position of the shuttle and capable of contacting the stops 4 on the buffers 5. In the conventional looms, said buffers 5, by moving back under the action of the stop-rod noses 3, cause the operating lever of the clutch to declutch the latter.

To effect the time-advanced stop motion, the buffer 5 according to the invention, is provided, for example, with a lateral ear 6 in the opening 15 of which is engaged one of the ends of a rod 7 the other end of which is pivoted at the free end of a small lever 8. This latter is pivoted on a pin 9 mounted near one of the extremities of a rocker beam 10 which may oscillate about its pivot 11. The other end of said rocker beam 10 is connected by a rod 12 to one of the ends of a second rocker beam 13 capable of oscillating about the pivot 14; the other end of said rocker beam 13 is pivoted at 15 on the rotatable and axially displaceable shaft 24 mounting the disc 25 of the clutch 16. The disc 25 is adapted to come into engagement with the cooperating disc 26. This clutch 16 is described more fully in the above mentioned co-pending patent application of even date Ser. No. 248,608.

The pivot 14 is mounted at the extremity of a connecting rod 17 the other extremity of which is pivoted on a pin 18 which is mounted on the housing of the clutch 16 or on another stationary part of the loom. The rocker beam 10 is permanently urged towards its rest position by a return spring 19 which causes a slide 20 to move along a fixed guide 21 on which are screwed the nuts 22, 23 forming an adjustable abutment for said return spring 19.

When the loom operates normally, and when the buffers 5 are in their initial rest position, the various elements of the mechanism, according to the invention, are at rest and have no action on the clutch. On the contrary, the moment the stop-rod noses 3 abut the stops 4 of the buffers 5 and initiate the backward movement of the latter, the rod 7 is moved longitudinally and causes the rotation of the lever 8 about its pin 9. However, said lever 8 is disposed so as to contact at its free end a frame part 24' of the loom. Therefore, the rotation of said lever 8 causes the rotation of the rocker beam 10 about its pivot 11 and against the action of the spring 19. Said rocker beam 10 exerts a pull on the second rocker beam 13

through the intermediary of the rod 12. The rocker beam 13 actuates the stop-motion mechanism at once by causing the separation between the driving and the driven discs.

From the foregoing it is apparent that the mechanism which has just been described is actuated as soon as the buffers begin their recoil movement, that is an instant after the stop-rod noses 3 have made contact with the stops 4 of the buffer 5. The declutching of the discs 25 and 26 is thus anticipated with regard to the stopping of the loom and it is time-advanced with regard to the normal declutching operation through the action of the operating hand lever (not represented) which is found in the known weaving looms. It is evident that the mechanical linkages between the buffer and the clutch mechanism may be modified in various manners, without departing from the spirit and scope of the appended claims, provided they operate to actuate the stop-motion mechanism upon the backward movement of the buffers before the loom is actually stopped and independently of the release of the manually operated declutching lever.

I claim:

1. In a weaving loom having a driving motor, a clutch mechanism associated with said motor, a batten and a buffer displaceable under the action of said batten, means for causing said clutch mechanism to take a declutched position, operable by said buffer upon an initial small displacement of the latter, comprising mechanical linkages connecting said buffer to said clutch mechanism whereby said motor will be declutched before said loom has actually stopped, said mechanical linkages including a rocker beam pivoted on the loom frame, a rod pivoted directly to the buffer at one end, a lever pivoted to one arm of said rocker beam, said rod pivoted at its other end to the free end of said lever, and a stationary member mounted on the loom and abutting the free end of said lever.

2. In a weaving loom having a driving motor, a clutch mechanism associated with said motor, a batten and a buffer displaceable under the action of said batten, means for causing said clutch mechanism to take a declutched position, operable by said buffer upon an initial small displacement of the same, comprising mechanical linkages connecting the buffer to said clutch mechanism whereby said motor will be declutched before said loom has actually stopped, said mechanical linkages comprising a rocker beam pivoted on the loom frame, a rod pivoted directly to the buffer at one end, a lever pivoted to one arm of said rocker beam, said rod pivoted at its other end to the free end of said lever, a stationary member mounted on the loom and abutting the free end of said lever, a second rocker beam having one arm connected to said clutch mechanism and the other arm connected to the other arm of said first mentioned rocker beam.

3. In a weaving loom having a driving motor, a clutch mechanism associated with said motor, a batten and a buffer displaceable under the action of said batten, means for causing said clutch mechanism to take a declutched position

operable by said buffer upon initial small displacement of the latter, comprising mechanical linkages connecting said buffer to said clutch mechanism whereby said motor will be declutched before said loom has actually stopped, said mechanical linkages comprising a rocker beam pivoted on the loom frame, a rod pivoted directly to the buffer at one end, a lever pivoted to one arm of said rocker beam, said rod pivoted at its other end to the free end of said lever, a stationary member mounted on the loom and abutting the free end of said lever, a second rocker beam having an arm connected to said clutch mechanism and the other arm connected to the other arm of said first mentioned rocker beam, a return spring urging said first rocker beam to a position corresponding to the clutching position of said clutch mechanism and means to adjust the tension of said spring, the latter being applied to said first mentioned arm of said first rocker beam at a point lying outwardly of the pivot connection of the said lever with said same arm.

4. In a weaving loom having a driving motor, a clutch mechanism associated with said motor, a batten and a buffer displaceable under the action of said batten, means for causing said clutch mechanism to take a declutched position, operable by said buffer upon an initial small displacement of the latter, comprising mechanical linkages connecting said buffer to said clutch mechanism whereby the motor will be declutched before said loom has actually stopped, said mechanical linkages comprising a rocker beam pivoted on the loom frame, a rod pivoted directly to the buffer at one end, a first lever pivoted to one arm of said rocker beam, said rod pivoted at its other end to the free end of said lever, a stationary member mounted on the loom and abutting the free end of said first lever, a second rocker beam having one arm connected to said clutch mechanism and the other arm connected to the other arm of said first rocker beam, a return spring urging said first rocker beam to a position corresponding to the clutching position of said clutch mechanism, means to adjust the tension of said spring, a second stationary element mounted on the loom, a second lever pivotally connected to the pivot of said second rocker beam at one end and pivoted on said second stationary element at the other end.

5. In a weaving loom as claimed in claim 4, wherein said spring is attached to said first mentioned arm of said first rocker beam at a point lying outwardly of the pivot connection of said first lever with said same arm.

JAIME PICANOL.
